UNITED STATES PATENT OFFICE.

FRANK F. KNOTHE, OF RIDGEWOOD, NEW JERSEY.

DESIGN FOR A BELT.

55,056.

Specification for Design.

Patented May 4, 1920.

Application filed July 2, 1917. Serial No. 178,259. Term of patent 14 years.

To all whom it may concern:

Be it known that I, FRANK F. KNOTHE, a citizen of the United States, residing at Ridgewood, Bergen county, State of New Jersey, have invented a new, original, and ornamental Design for a Belt, of which the following is a specification, reference being had to the accompanying drawing, forming part thereof.

The figure is a perspective view, taken from one side, of a belt showing my new design.

I claim:

The ornamental design for a belt as herein set forth.

FRANK F. KNOTHE.
